UNITED STATES PATENT OFFICE.

JOHN E. LAVALLEY, OF PORTLAND, OREGON.

TELEPHONE-LOCK.

1,172,614.

Specification of Letters Patent. Patented Feb. 22, 1916.

Application filed May 18, 1915. Serial No. 28,887.

To all whom it may concern:

Be it known that I, JOHN E. LAVALLEY, a citizen of the United States, residing at Portland, in the county of Multnomah and State of Oregon, have invented certain new and useful Improvements in Telephone-Locks, of which the following is a specification.

My invention relates to new and useful improvements in locks for telephones, the primary object of my invention being the provision of a lock applicable to telephones of the desk type which, when in place, will prevent unauthorized use of the telephone. Oftentimes, telephone subscribers, upon a limited call basis, find that their bills are much higher than they believe proper, this generally being due to the use of the telephone by others and being particularly common with telephones in offices, stores and similar places.

The primary object of my invention consists in the provision of a simple device which may be readily applied to or completely removed from a telephone instrument of the desk type and which, when applied, will absolutely prevent upward movement of the receiver supporting hook and, consequently, prevent use of the telephone instrument.

A further object of my invention consists in constructing a device of the above character in the form of a collar adapted to embrace the standard of the instrument and to engage at one edge beneath the shoulder at the upper end of the standard and at its other edge against the receiver supporting hook.

A still further object of my invention consists in forming the collar in a number of sections hingedly connected and in providing the free end of one section with a lock mechanism and the free end of the other section with a hook or latch member engageable by the lock mechanism.

A still further object of my invention consists in providing the lower edge of the locking collar with a notch or slot to receive the receiver holding arm of the telephone instrument and the inner face of one of the collar sections with a stud or projecting shoulder insertible in the slot formed in the standard of the instrument through which the receiver supporting arm projects.

With these and other objects in view, my invention will be more fully described, illus-

trated in the accompanying drawings, and then specifically pointed out in the claims which are attached to and form a part of this application.

In the drawings: Figure 1 is a fragmentary perspective view of a conventional form of telephone instrument of the desk type, showing my improved lock applied thereto; Fig. 2 is a vertical, sectional view taken through the standard of the telephone instrument and locking collar; Fig. 3 is a perspective view of my locking collar removed from the instrument and in open position showing the inside construction of the collar; Fig. 4 is a longitudinal sectional view through one of the terminal members of the collar, showing the lock structure and the key which is employed in connection with the lock.

Corresponding and like parts are referred to in the following description and indicated in all the views of the drawings by the same reference characters.

In order to insure a clear and accurate understanding of my invention and its application, it is necessary that a comprehension of the construction of an ordinary telephone instrument of the desk type be had. In Figs. 1 and 2 of the drawings I have illustrated the tubular standard portion 10 of a desk telephone, which portion incloses the current carrying wires and the receiver arm operated switch by means of which the instrument is put in communication with the telephone line. The upper end of this standard is closed by a head 11 which projects peripherally beyond the standard, as shown at 12, and which carries the transmitter 13. The standard, adjacent the head 11, is formed with a vertical slot 14 through which passes the receiver supporting arm 15, the weight of the receiver, when in the receiver hook 16, holding such hook in lowered position and the switch within the standard 10 in open position. A spring, not shown, is provided for moving the hook to raised position upon removal of the receiver 17 to automatically close the circuit between the instrument and telephone line.

My invention, in the present instance, consists in the provision of a locking collar which may be applied to the standard portion of the telephone instrument between the head 11 and receiver supporting arm 15 and locked in place to lock the receiver supporting arm in lowered position.

More specifically, my invention includes a locking collar, indicated as a whole by the numeral 18, and including an intermediate body portion 19 and end portions 20 and 21. 5 The intermediate body portion is arcuate to correspond to the cross sectional curvature of the standard 10 and at its ends is formed with spaced ears 22 adapted to engage between correspondingly formed ears 23 upon 10 the adjacent ends of the terminal sections 20 and 21 of the collar. The sections are hingedly connected by pintle pins 24 passed through the intermeshing ears of the sections. 15 As previously stated, the intermediate section is arcuate and as will be noted by reference to Fig. 2, the adjacent end portions of the terminal sections are also curved somewhat in order that one end of the section 20 20 may rest flatly against the end portion of the inner face of the section 21 when the collar is closed about the standard, as shown in Fig. 1, the ends of the terminal sections, therefore, being at right angles to each 25 other.

The collar is slightly greater in height than the distance between the upper face of the receiver supporting arm 15 when the latter is in lowered position and the peripherally projecting flange 12 of the head 11. 30 The lower edge of the intermediate section 19 of the collar is provided with a notch or slot 25 to receive the receiver supporting arm 15 and projecting from the inner face 35 of such section and in vertical alinement with the notch 25, is a stud or shoulder 26 which projects into the upper end of the slot 14 when the collar is applied, this notch and stud co-acting to hold the collar against 40 movement when applied and thereby, to a great extent, prevent any tampering with the device by an unauthorized person.

The terminal section 20 of the collar, at its free end, has its outer face cut-away to receive the face plate 27 of a lock mechanism 28, such mechanism being inclosed in a recess 29 formed in the outer face of the section 20 by the face plate which is secured by screws 30 or other suitable fastening devices, leaving the free end of the recess or lock mechanism containing socket open, as clearly shown in Fig. 3. Rigidly secured in the socket or recess 29, is a leaf spring 31, the free end of which projects toward and 55 nearly to the open end of the socket, terminating in a hook portion 32. The lower wall of the collar section 20 is provided with a slot 33 through which the shank 34 of a key 35 may pass and to prevent use of 60 any key other than the one intended or any other instrument in releasing the lock. This slot is preferably provided with one or more shoulders 36 and the shank of the key formed with longitudinal grooves or channels 37 to receive the shoulders, as is com-

mon in the manufacture of locks. Furthermore, the key shank preferably has its free end narrowed or rounded off, as shown at 38, in order that it will not interfere with proper bending of the spring 31 upon forcing the key shank against such spring. 70

The opposite terminal section 21 of the collar, adjacent its free end, has formed upon its inner face a centering stud or pin 39 adapted to enter the upper portion of the open end of the lock socket 29 and a vertically alined hook or latch member 40 adapted to enter the lower portion of such socket and be lockingly engaged by the hooked terminal 32 of the locking spring 31, as 80 clearly shown in Fig. 4. The free end or hook portion of the latch or hook 40 has its outer face cut-away, as shown at 42, whereby it is reduced in thickness to permit the passage of the key shank into engagement 85 with the locking spring 31.

In use, when the telephone instrument is to be locked, the locking collar, unless already unlocked is unlocked by insertion of the key 35 in the lock to force the locking 90 spring 31 out of engagement with the hook 40. The collar is then swung to open position, as shown in Fig. 3, and with the receiver 17 still on the hook 16, the intermediate section of the collar is seated upon the receiver arm 15, such arm engaging in the slot 25. The intermediate portion of the collar is then swung or pushed into engagement with the standard portion 10 of the telephone instrument until it bears between 95 the receiver arm and flange 10 and until its shoulder or stud 26 seats in the upper end of the slot 14. The terminal sections 20 and 21 of the collar are then swung to bring their free ends together to the position shown in 100 Fig. 1 when the hook 40 enters the socket 28 and is automatically engaged by the locking spring 31. It will be readily apparent that with the collar locked in place in this manner, it will be impossible to raise the receiver arm 15 and, consequently, all use of the telephone instrument will be prohibited. The owner can readily remove the collar at any time by merely forcing the shank of the key 35 through the key slot 33 and into 115 engagement with the locking spring 31 to force it out of locking engagement with the hook 40.

Although I have illustrated and described my invention in all its details of construction, it will of course be understood that I do not wish to be limited to such details as various minor changes, within the scope of the appended claims, may be made at any time, without in the slightest degree departing from the spirit of my invention. 120

Having thus described the invention, what is claimed as new is:

1. A locking device for desk telephones including a locking collar having an inter- 130

- mediate section and terminal sections hingedly connected to the ends of the intermediate section, the collar being adapted to surround the standard portion of the instrument and engage between the receiver supporting arm and head portion of the instrument to hold the arm in lowered position, the intermediate portion of the collar being formed with a receiver supporting arm receiving slot and the end portions of the collar being shaped to abut against each other at substantially right angles when the collar is closed, and locking means for securing the end portions together.
- 10 15 2. A locking device for desk telephones
- including a collar having an intermediate receiver supporting arm engaging section and terminal sections hingedly connected to the ends of the intermediate section, the sections being shaped in such a manner that 20 the free ends of the terminal sections may abut each other when the collar is closed, and coacting means carried by the terminal sections for interlocking engagement.
- 25

In testimony whereof I affix my signature in presence of two witnesses.

JOHN E. LAVALLEY. [L.S.]
